UNITED STATES PATENT OFFICE.

GOTTHOLD BLOCH, OF BROOKLYN, NEW YORK, ASSIGNOR TO NATIONAL ENAMELING & STAMPING COMPANY, OF NEW YORK, N. Y., A CORPORATION OF NEW JERSEY.

REINFORCED NOZZLE FOR SHEET-METAL CONTAINERS.

1,226,605.

Specification of Letters Patent.

Patented May 15, 1917.

Application filed October 14, 1915. Serial No. 55,788.

To all whom it may concern:

Be it known that I, GOTTHOLD BLOCH, a citizen of the United States, residing at Brooklyn, in the State of New York, have 5 invented certain new and useful Improvements in Reinforced Nozzles for Sheet-Metal Containers, of which the following is a specification.

This invention relates to a nozzle or neck 10 applied to a reinforced opening in sheet-metal containers.

Numerous kinds of containers such as barrels, or casks, are manufactured of sheet-steel, and have a nozzle or neck provided 15 with a screw-thread for engagement of a plug, spigot or other closure device. In many cases the metal-shell of the container is too thin to permit of cutting a screw-thread with which a spigot may engage.

20 The desideratum which this invention supplies is a reinforced nozzle or neck partly formed of the thin sheet-metal of a barrel or cask, and projecting therefrom, and screw-threads cut on said nozzle to receive 25 a spigot or other closure device.

My invention, therefore, has for its object to provide on thin sheet-metal containers an improved formation of nozzle or neck.

The invention is illustrated in the accompanying drawing wherein,—

30 Figure 1, shows a sheet-metal article, such as the head of a barrel, can or cask, provided with my improved reinforced hole connection.

35 Fig. 2, illustrates in cross-sectional detail the reinforcing plate employed in carrying out my invention.

Fig. 3, shows the same in plan view.

40 Fig. 4, is a cross-sectional detail through the hole in the barrel-head and illustrates one step that may be taken in the preparation of the sheet-metal preparatory to receiving the reinforcing plate.

45 Fig. 5, shows another step in which the reinforcing plate and the prepared sheet-metal head are secured together.

Fig. 6, shows a cross-sectional view 50 through the barrel-head and its hole and illustrates another step in producing the improved reinforced hole and neck.

Fig. 7, shows a cross-sectional detail 55 through the neck and joint hole, partly formed by the sheet-metal of the container, and where a screw-thread is formed on the neck.

In commercially practising the invention in making barrels of sheet-steel, I prefer to form a circular or other shaped shallow recess 8, on the inner surface of the sheet-metal head 9, at the place where the hole 60 is to be formed, and at the center of this recess a circular perforation or opening 10, is to be formed at some stage of the method. The formation of the recess 8, at the inner surface of the thin sheet-metal produces a 65 correspondingly shaped projection 11, on the exterior surface of the metal. This recessing step, however, is not essential, but for some of the products of this method it is preferred.

70 On the inner surface of the sheet-metal barrel-head 9, I secure a reinforcing plate 12, in direct contact with said surface. The reinforcing plate, 12, and the sheet-metal head 9, are secured together, preferably by so-called electric spot-welds which are indicated at 14, so as to permanently secure the 75 two plates together.

The reinforcing plate 12, must have an 80 opening 13, whose position will register or coincide with the perforation or opening 10, in the barrel-head 9. Initially the opening 13, in the reinforce will be smaller in diameter than the said opening 10, in the barrel-head, as seen in Fig. 5, of the drawing.

85 It will be seen the reinforcing plate 12, in the present instance, has a greater thickness than the metal of the barrel-head 9, which affords the advantage of enabling screw-threads, if the same are desired, to 90 be cut in the metal of the reinforcing plate alone.

95 In the present instance the reinforcing plate 12, is bendable and has the form of a disk or circular washer, of a diameter to enable it to enter and fit within the recess 8, when the later is employed.

100 The hole or opening 13, in the reinforce plate or disk is to be formed at some convenient stage of the construction.

105 The appearance of the article (in this instance a barrel-head) when it has been subjected to the next step of the construction, is illustrated in Fig. 6. This step consists in the employment of a suitable die and punch to expand the metal around the two openings 10 and 13, in the barrel head 9, and bendable plate 12, respectively, and this expanded metal being forced outwardly forms a double-thick straight nozzle 15, that pro- 110

jects on the outer side of the barrel-head; the internal nozzle and the flat flange of the bendable plate are connected integrally by metal which curves from said flange into the nozzle, as shown in Fig. 6.

That part of the described procedure of construction that includes the spot-welds 14, to hold the two thicknesses of metal together, and then the action of drawing and expanding dies to simultaneously draw the said two thicknesses of sheet-metal, results in so closely uniting the contacting surfaces of the two sheet-metal plates, as to insure a liquid-tight joint or union at said surfaces. It will be seen the nozzle or neck 15, is formed of two thicknesses of sheet-metal and the inner thickness, in the present instance, is thicker than the outer thickness.

The final step in this construction is to cut a screw-thread 16, within the nozzle or neck 15; this is done by employing well-known screw-thread-cutting tools.

It will be seen the circular reinforcing plate 12, has a round open tube that projects from its center and fits tightly as a lining into the nozzle formed of the sheet-metal of the container.

A plug with a screw-thread, or a spigot with a screw-thread may be attached as a closing device.

It is obvious that nozzle parts such as those herein described may have a screw-

thread cut either internally of the nozzle or externally.

Having described my invention what I claim is,—

The combination with a sheet metal container having a circular opening in its wall and the metal of the wall about the opening being forced outwardly to form a nozzle that is smooth on both the interior and the exterior, and on the inner side said receptacle-wall being pressed outwardly to form an annular interior recess around the opening, and a plate having an interior portion which seats in the interior recess of the receptacle wall and said plate being pressed outwardly from the said flange and through the nozzle,—the outer surface of the outwardly-pressed central portion of the plate being in close contact with the smooth interior of the nozzle portion of the receptacle wall and the inner surface of said outwardly-pressed portion of the plate having screw threads and the flange portion of the plate being permanently secured in the interior recess of the receptacle wall.

In testimony whereof I affix my signature in presence of two witnesses.

GOTTHOLD BLOCH.
